VALENTIN CONSTANT TENEAU, OF PELHAM, NEW YORK.

DESIGN FOR PLAYING-CARD HOLDER.

Application filed March 7, 1927. Serial No. 20,998. Term of patent 14 years.

To all whom it may concern:

Be it known that I, VALENTIN CONSTANT TENEAU, a citizen of France (but having taken out his first papers with the intention of becoming a citizen of the United States), residing at Pelham, county of Westchester, and State of New York, have invented a certain new, original, and ornamental Design for Playing-Card Holder, of which the following is a specification, reference being had to the accompanying drawing, forming part thereof.

Figure 1 of the drawing shows a front

elevation of a playing card holder embodying my new design; and,

Figure 2 is a transverse section on the line 2—2 of Figure 1.

The dominating feature is the two partial discs superimposed with the cutaway portions thereof coincident leaving the angular space extended inward from the periphery thereof.

I claim:

The ornamental design for playing card holder, as shown and described.
